CLAIM

The ornamental design for a front sight for firearm, as shown and described.

DESCRIPTION

FIG. 1 is a perspective view taken from the top and rear of the front firearm sight showing my new invention. The broken line showing the front of a firearm is for illustrative purposes only and forms no part of the claimed design; FIG. 2 is a front elevational view thereof; FIG. 3 is a rear elevational view thereof; FIG. 4 is a side elevational view thereof, the opposite side being a mirror image thereof; FIG. 5 is a top elevational view thereof; and, FIG. 6 is a bottom elevational view thereof.
